UNITED STATES PATENT OFFICE

ST. CLAIR C. HOLLAND, OF MONTREAL, QUEBEC, CANADA, ASSIGNOR TO THE ROBERT MITCHELL COMPANY LIMITED, OF MONTREAL, CANADA

CHARCOAL BURNER

Application filed October 5, 1929. Serial No. 397,638.

This invention relates to certain new and useful improvements in charcoal burners of the character disclosed by Allan M. Mitchell in his prior patent application, Serial No. 5 312,638, filed October 15th, 1928, which has matured into Patent No. 1,745,109, Jan. 28, 1930.

An object of the invention is to provide a burner in which the fire may be completely 10 extinguished in a relatively brief period of time through the agency of a damper controlling both the inflow of combustion supporting air and the outflow of combustion gases.

Another object is to provide a damper 15 which is adjustable to accelerate or retard the progress of combustion within the burner.

A further object is to provide a damper 20 which, in closed position, causes the fire to die out in a comparatively short time and also prevents the fire from creeping up into the magazine and consuming the fuel therein.

A further object is to provide an improved 25 baffle arrangement functioning to force practically all of the inflowing air to the bottom of the burner and beneath the fire pot.

A still further object is to provide an air 30 directing baffle arranged between the fire pot and the air admission openings and equipped with a spark intercepting flange serving to prevent the passage of sparks outwardly through said openings.

Still a further object is to provide a lighting 35 tray mounted to slide from a position beneath the grate to an accessible position adjacent the fire door opening.

Other objects, as well as the advantages and 40 novel characteristics of the invention, will be readily understood from the following detailed description taken in connection with the accompanying drawings, in which:

Figure 1 is a view, partly in side elevation, and partly in vertical section, of a burner constructed in accordance with my invention.

Figure 2 is a transverse sectional view taken 45 on the line 2—2, Figure 1.

Figure 3 is a fragmentary view in side elevation, showing the mounting of a damper.

Figure 4 is a fragmentary transverse sectional view taken along the line 4—4 of Figure 3.

Figure 5 is a fragmentary transverse sectional view taken along the line 5—5, Figure 3.

Figure 6 is a longitudinal sectional view of the lighting tray and supporting means 55 therefor.

Figure 7 is a transverse sectional view taken along the line 7—7, Figure 6.

The cylindrical outer casing or shell of the burner is indicated at 12. A top plate 13 65 closes the upper end of the shell and is provided with a central opening 14 through which fuel is inserted in the fuel magazine 15. Opening 14 is closed by an airtight cover 16, held in place in any suitable manner.

The bottom of fuel magazine 15 is formed by a hopper 17 having a central opening 18 through which the fuel passes into a fuel tube 19. The lower end of tube 19 is secured to a centrally apertured cone 20, forming the top 70 of a fire pot 21. Suitable brackets 20^a are provided for supporting the cone 20 from, and in spaced relation to, the shell 12. The conical grate 22 of the fire pot is suspended from cone 20 by bolts 23 passing through lugs 75 24 and the flange 25. The annular wall 26 of the fire pot is clamped between cone 20 and flange 25. Both cone 20 and the annular wall 26 are provided with apertures 27.

The lower end of shell 12 is closed by a 80 plate 28 which is preferably made of asbestos to protect the floor surface on which the burner is mounted. A false bottom in the nature of a metal plate 29 is arranged upon the plate 28 and is supported from the latter by any 85 suitable form of supporting members 30. The plate 29 forms the bottom wall of the ash space 31 and is also utilized to support the lighting tray structure hereinafter referred to. Access to space 31 is afforded by 90 a doorway 32 controlled by any suitable form of sliding door 33 fitted between guides 34.

The lighting tray 35 is slidably mounted beneath the grate 22. The details of the mounting or supporting means for the tray 95 are shown to advantage in Figures 1, 6 and 7. Said mounting or supporting means comprises an outer inverted U-shaped member which presents a horizontal top plate 37 and dependent parallel side members 38. The 100

lower edges of side members 38 are turned outwardly to provide supporting feet 39, which, as illustrated in Figure 1, rest on and are suitably secured to the aforesaid plate 29. 5 Nested within the outer member 36 is an inner member 40 of similar shape. Member 40 presents a top plate 41 spaced from the top plate 37 and dependent side members 42 engaging the inner surfaces of side members 38 and riveted or otherwise secured thereto. The 10 space reserved between plates 41 and 37 provides a guide channel slidably receiving the shank 43 of the lighting tray 35. This shank is provided with a depending stop lug 45 operating in a longitudinal slot 46 formed in plate 41. The end walls of the slot co-operate with the stop lug to limit the sliding movement of the tray. The tray is normally positioned directly beneath the grate 22, but, for 15 refilling purposes, may be pulled outwardly to an accessible position in close proximity to the fire door opening 32.

In order to provide for the inflow of the necessary combustion-supporting air and the 20 outflow of gases, or products of combustion, the shell 12 is provided at one side with a plurality of openings 48. These openings are controlled by a damper structure comprising a base plate 49 and a rotatable damper plate 50, both of which are of circular form. The 25 base plate 49 is bolted, or otherwise firmly secured to the shell, and is provided with a plurality of openings 51 registering with the shell openings 48. An asbestos gasket is 30 preferably interposed between base plate 49 and shell 12, as indicated at 52.

Damper plate 50 is rotatably secured to base plate 49 by a central pivot pin 54, affording a horizontal axis about which the damper 35 plate may be turned to various positions of adjustment. Spaced openings 55 formed in the damper plate 50, are adapted to be moved into and out of registration with the openings 51. The central portion of damper 50 is provided with an outwardly projecting collar 56 in which is arranged a coil spring 57 encircling the outer portion of pivot pin 54. This spring is held in compression between the outer surfaces of damper plate 50 and a 40 thrust washer 58 carried by the outer end of pivot 54 and engaging the head 54^a of said pivot. By reason of the spring pressure thus created, damper plate 50 is held in such frictional contact with base plate 49 as to maintain any position to which it is adjusted.

The damper mechanism hereinbefore described affords a novel means of control as applied to charcoal burners. When the maximum degree of draft is desired, the openings 45 55 are brought into full registration with openings 51, thus accelerating combustion within the burner to the maximum degree. When it is desired to regulate or retard the progress of combustion, this is accomplished 60 by rotating the damper plate so that the solid

portions 59 separating the openings 55 are positioned to partially cover or throttle the openings 51 to the desired extent. When the damper plate 50 is shifted to a position where the solid portions 59 fully cover the openings 70 51, the inflow of combustion supporting air and the outflow of gases is completely arrested, with the result that the fire in the burner is caused to die out in a comparatively brief period of time. Complete closure of 75 the damper also prevents the fire from creeping up into the magazine and consuming the fuel therein.

In order to limit the turning movement of the damper plate 50, in either direction, I 80 may provide said plate with a stop pin 50^b co-operating with suitable stops 49^a carried by the base plate 49.

Improved baffle means are also provided for directing practically all of the incoming air to the bottom of the burner and beneath grate 22. Said baffle means comprises a body plate 61 which is positioned as shown in Figure 1, wherein it will be noted that the upper end of the plate is located in a plane coinciding with the longitudinal axis of the damper pivot 54, while the lower end of said plate projects a short distance below the grate 22. Plate 61 extends entirely across the burner but in spaced relation to that portion of the shell 12 in which the openings 48 are formed. Said plate is connected to the shell by means of side walls 62 having suitable attaching lugs 63 riveted or otherwise secured to the shell. During the operation of the burner, practically all of the inflowing combustion-supporting air is drawn downwardly through the comparatively restricted passage 64, bounded by plate 61, side walls 62 and shell 12, and is delivered beneath the 90 100 grate 22. At its upper end, plate 61 is provided with a horizontal flange 65 bridging the space reserved between said plate and the upper end of the fuel tube 19. Flange 65 is made long enough to extend entirely across the burner and the terminals of the flange are curved, as indicated at 66, to fit closely against the inner surface of the shell 12.

During the operation of the burner, practically all of the combustion-supporting air, as previously explained, passes downwardly through the passage 64 and beneath the grate 22. The gases, or products of combustion, escape from the fire pot and circulate around the space 67 before finding an outlet through the upper damper openings 48. The plate 61 and flange 65 are so positioned with reference to the fire pot and the openings 48 as to serve as a spark intercepting means for preventing the direct passage of sparks outwardly through said openings.

Having thus fully described what I now consider to be the preferred embodiment of my invention, it will be understood that va- 115 120 125 130

rious changes in the construction, combination and arrangement of parts, may be resorted to, within the scope and spirit of the invention, as defined by the appended claims.

5 Having thus described my invention, what I claim is:

1. A magazine burner of the character described, including means for shutting off the inflow of combustion supporting air and the outflow of combustion gases, whereby the fire in the burner is caused to die out quickly and is prevented from creeping into the magazine and consuming the fuel therein, said means including a single movable damper element controlling both the air inflow and the gas outflow openings.

10 2. A burner of the character described, comprising a shell provided with a plurality of closely grouped air inflow and gas outflow openings, a single movable damper plate provided with openings shiftable into and out of registration with the shell openings and means for holding the damper plate in various positions of adjustment with respect

25 to said shell openings.

30 3. A burner of the character described, comprising an outer shell, a fuel magazine located in the upper portion of said shell, a fire pot positioned below the magazine and communicating therewith, said shell being formed with a plurality of closely grouped air inflow and gas outflow openings establishing communication between the atmosphere and an air space within the shell sur-

35 rounding the fire pot and the lower portion of the fuel magazine, a damper plate controlling said openings, and a baffle arranged to direct the inflowing air to the bottom of the heater and beneath the fire pot.

40 4. A burner of the character described, comprising a shell having a group of openings formed in a restricted area thereof to provide for the inflow of combustion supporting air and the outflow of combustion gases, and means operable to partially or completely close all of said openings so as to regulate or completely shut off the flow of air and gases therethrough.

45 5. A burner of the character described, comprising a shell, a magazine in the upper portion of said shell, a fire pot in the lower portion of the shell arranged to receive fuel from the magazine, said shell being provided in one side with a plurality of closely grouped openings for the inflow of combustion supporting air and the outflow of combustion gases, an adjustable damper plate controlling all of said openings, and a baffle plate arranged in the shell to form a restricted air

55 60 65 passage leading downwardly from a point directly opposite said openings to a point adjacent the bottom of the burner.

6. A burner as recited in claim 5, in which the baffle is provided with a flange arranged

as to prevent the passage of sparks outwardly through the aforesaid openings.

7. A burner of the character described, comprising a shell having a magazine in the upper portion thereof, a fire pot arranged in the lower portion of the shell to receive fuel from said magazine, the upper portion of said shell being provided at one side with a plurality of closely grouped openings for the inflow of combustion supporting air and the outflow of combustion gases, and a baffle structure arranged in the shell in such relation to the fire pot and to the said openings as to cause practically all of the inflowing combustion supporting air to be directed to the bottom of the burner and beneath the fire pot, said baffle structure including provision for preventing passage of sparks outwardly through the aforesaid openings.
